UNITED STATES PATENT OFFICE.

ORA E. HECKMAN, OF AKRON, OHIO.

TRIMMING DEVICE FOR RUBBER-CLOTH AND THE LIKE.

1,216,315.

Specification of Letters Patent. Patented Feb. 20, 1917.

Application filed February 21, 1916. Serial No. 79,506.

To all whom it may concern:

Be it known that I, ORA E. HECKMAN, a citizen of the United States, residing at Akron, in the county of Summit and State 5 of Ohio, have invented a new and useful Trimming Device for Rubber-Cloth and the like, of which the following is a specification.

My invention relates to trimming devices for rubber cloth and the like and has more 10 especial reference to a device adapted to cut sheets of rubber cloth into the proper size and shape for the manufacture of inner tubes for vehicle tires.

The object of the present invention is to 15 provide a machine which will trim thin sheets of india rubber to the proper size and shape for the manufacture of inner tubes for tires.

A further object is the provision of a machine 20 of the character referred to in which the dies are interchangeable and adjustable with reference to each other in order that different sizes of sheets may be cut for various sizes of tires.

With these objects in view the invention 25 consists in the novel construction and arrangement of parts, hereinafter described, illustrated in the accompanying drawings, and particularly pointed out in the appended 30 claims, it being understood that various changes in the form, proportions, size and minor details of construction may be made within the scope of the appended claims, without departing from the spirit or sacrificing 35 any of the advantages of the invention.

In the accompanying drawings:

Figure 1 is a top plan view of my improved trimming device.

Fig. 2 is a longitudinal sectional view of the same.

Fig. 3 is a rear elevation of the same.

Fig. 4 is a section on the line 4—4, Fig. 1.

Fig. 5 is a plan view of the die which 45 forms the first operation.

Fig. 6 is a plan view of the die which forms the second operation.

Fig. 7 is a plan view of one of the finished sheets of rubber.

Similar numerals of reference indicate corresponding parts throughout the several figures of the drawings.

In the drawings the numeral 1 indicates a 50 rectangular frame, preferably formed of angle iron, which is supported upon suitable standards 2. The table is composed of the

two stationary sections 3 and 4, preferably formed of wood and the filler sections 5, any number of which may be placed in position within the rectangular frame as shown in 60 the drawings, the number of these filler sections used depending upon the length of the sheet of rubber to be trimmed upon the table.

The die 6 is located in the frame 1 between the sections 3 and 4 of the bed plate 65 and coacts with the reciprocating knife 7, said knife being provided with a sleeve 8, which is slidably mounted upon the vertical post 9, said post being fixedly connected to the frame 1. A pitman rod 10 is pivotally 70 connected to the sleeve 8 and to the pitman wheel 11 by means of the wrist pin 12, said pitman wheel being mounted upon the horizontal shaft 13, which shaft is journaled in suitable bearings 14 carried upon the under 75 side of the frame 1, an operating crank 15 being provided upon the forward end of the shaft.

A block 16 is slidably mounted between the side members of the frame, said block 80 being provided with an inclined table portion 17 adapted to be located upon the filler sections 5. A die 18 is formed upon the block 16 and coacts with the reciprocating knife 19, said knife being provided with a 85 sleeve 20 slidably mounted upon a post 21, said post being carried upon the block 16. The pitman rod 22 connects the sleeve 20 with the pitman wheel 23, said pitman wheel being mounted upon a horizontal shaft 24 90 journaled in suitable bearings 25, which are located on the underside of the block 16, an operating crank 26 being provided upon the forward extremity of the shaft 24.

The block 16 is provided on its under face 95 with an internally screw threaded lug 27, which engages the screw threaded shaft 28, said shaft being journaled in a suitable bearing 29 carried at one end of the frame 1, collars 30 being fixedly connected to said 100 shaft upon each side of the bearing for the purpose of preventing longitudinal movement of the shaft and an operating wheel 31 being provided upon the extremity of the shaft for the purpose of rotating the same. 105 A scale 32 is provided upon one side of the frame for the purpose of indicating the amount of adjustment necessary for cutting strips of different lengths.

Rubber cloth from which the strips are 110 cut is carried on a stock roll located at the left hand end of the trimming device above

described and the cloth is unrolled from the stock roll and spread beneath the cutting knives upon the table, the inclined portion 17 being provided for the purpose of preventing any break between the filler sections and the block 16 as when the rubber is in an uncured condition, a ridge or groove would be formed in the rubber by allowing it to remain for a short length of 10 time over any uneven surface. The cranks 15 and 26 are then operated cutting the left hand end of the rubber strip entirely across and forming the same as shown in Fig. 7. As the next length of the strip is placed beneath the knives the right hand end of the rubber strip which is located beneath the knife 19 will be of the form shown in dotted lines Fig. 7 and as the knives again descend the left hand end of the strip will be formed 20 as shown in Fig. 7 while the knife 19 will cut out the rectangular portion indicated in dotted lines in said figure the finished sheet being of the form shown in Fig. 7.

After the gum sheets are trimmed as 25 above described, they are placed in what is known as a book. When the book is filled it is taken to a table and the sheets are rolled on a mandrel, each sheet forming a two ply tube, the ends of which are of a single ply, 30 thus forming a step at each end, the tube upon the mandrels is then placed upon a wrapping lathe and wrapped and by wrapping with the proper tension the stepped ends will be drawn to a taper doing away 35 with the skiving after the tube is cured and ready for finishing.

Although the drawings and above specification disclose the best mode in which I have contemplated embodying my invention 40 I desire to be not limited to the details of such disclosure, for, in the further practical application of my invention, many changes in form and construction may be made, as circumstances require or experience suggests, 45 without departing from the spirit of the in-

vention, within the scope of the appended claims.

I claim:

1. In a machine of the character described, a frame, a table mounted in said frame, a die slidably mounted in said frame adjacent one extremity of said table, a cutting knife coöperating with said die and an inclined plate carried by said die and arranged to slide upon the upper surface of 55 said table.

2. In a machine of the character described, a frame, a table mounted in said frame adjacent one end thereof, a block slidably mounted in said frame adjacent one 60 end of said table, a die mounted upon said block, a cutting knife mounted upon said block and coöperating with said die, and an inclined plate carried by said block and arranged to slide upon the upper surface of 65 said table.

3. In a machine of the character described, a frame, a table mounted in said frame adjacent one end thereof, a block slidably mounted in said frame, a die mounted upon said block, a cutting knife mounted upon said block and coöperating with said die, and removable filler blocks located in 70 said frame between said table and said slideable block.

4. In a machine of the character described, a frame, a table mounted in said frame, adjacent one end thereof, a block slidably mounted in said frame, a die mounted upon said block, a cutting knife mounted 75 upon said block and coöperating with said die, filler blocks located in said frame between said table and said slideable block and an inclined plate carried by said slideable block and arranged to slide upon the upper 80 surface of said filler blocks.

In testimony that I claim the above, I have hereunto subscribed my name.

ORA E. HECKMAN.
